UNITED STATES PATENT OFFICE

2,415,081

LIQUIDPROOF PAPER CONTAINER

Lewis C. Brooks, Madison, Wis., assignor of one-third to Ira Milton Jones, Mequon, Wis.

Application October 23, 1942, Serial No. 463,109

7 Claims. (Cl. 229—17)

1

This invention relates to paper containers and refers particularly to paper containers designed for public dispensing of milk and other liquid food products.

Paper milk containers have been used in the past. Some of them have flat top and bottom walls, which is desirable from the standpoint of facilitating handling and particularly the stacking of the filled containers; but many of the paper containers heretofore in use for milk distribution do not have flat top walls.

In all of the paper containers heretofore in use for this purpose difficulty has been experienced in providing a convenient pouring opening. This disadvantage is particularly prevalent in that type of container in which the top is not flat as in the bag type containers like that illustrated in the patent to Scott No. 2,006,689.

In paper containers of the type represented by the patent to Hothersall No. 2,085,979, in which the top wall is flat, special provision is made for a pouring opening, but the construction of these containers is such that the opening is located wholly within the confines of the top which results in an objectionable ledge across which the contents must be poured.

Moreover, that type of container illustrated in the Hothersall patent has its top and bottom walls formed separately from the side walls and secured thereto in the formation of the container. As a result, this type of container cannot be shipped flat for erection at the point of use as are containers of the one-piece blank type.

In recognition of the deficiencies of these past containers, the present invention has as one of its objects the provision of a paper container suitable for public distribution of milk and other liquid products which, although of the single blank type like the container of the Scott Patent 2,006,689, has flat top and bottom walls and facility for convenient pouring of its contents.

More specifically, it is an object of this invention to provide a liquid tight paper container having a flat top wall with a corner portion thereof formed as a hinged flap adapted to be lifted to an open position to provide a pouring opening at the extreme corner of the container.

Another object of this invention is to provide a novel manner of sealing the cover opening under the hinged cover flap so that the flap need not be secured down tight, but can be held closed by a readily broken seal.

Another object of this invention is to provide reinforced rounded corners for the top marginal edges of the side walls of the container which define the pouring opening.

A further object of this invention is to provide a container having these desirable char-

2

acteristics which is formed entirely from a single blank and which when erected and coated with paraffin or other similar waterproofing substance is exceptionally strong and rigid.

Still another object of this invention is to provide a one piece container of the character described which is so constructed that both top and bottom closures are readily formed over internal supports.

In this connection it is an object of this invention to so construct the container that a relatively large opening is provided through which expansible internal supporting tools may be inserted and which by its large size facilitates paraffining of the container.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate two complete examples of the physical embodiment of the invention constructed according to the best mode so far devised for the practical application of the principles thereof, and in which:

Figure 1 is a perspective view of a container embodying this invention and illustrating the same opened for emptying its contents;

Figure 2 is a perspective view of the upper portion of the container with parts broken away to more clearly illustrate the cover construction;

Figure 3 is a plan view of the blank in its flat form;

Figure 4 is a plan view of a slightly modified blank;

Figure 5 is a perspective view illustrating the container which the blank of Figure 4 forms, partially set up;

Figure 6 is a perspective view of the completed container showing the manner in which final sealing is effected;

Figure 7 is a fragmentary perspective view of the sealed container to show the use of a temporary seal to hold the closure flap in its closed position;

Figure 8 is a fragmentary perspective view like Figure 7 showing another manner of holding the closure flap down; and

Figure 9 is a fragmentary perspective view of the upper portion of a container illustrating a slightly modified construction for the pouring opening.

Referring now particularly to the accompanying drawings, in which like numerals indicate like parts, it will be seen that the blank B comprises four vertical side panels 5, 6, 7 and 8 defined from each other by score lines 9, 10 and 11.

A glue lap 12 extends along the free edge of side panel 5 being defined therefrom by a score line 13. In forming the container this glue lap is adhered to the free edge of the side wall 8, as is customary.

Extending across the bottom of the blank is a score line 14 which defines three marginal flanges or laps 15, 16 and 17 on the lower marginal edge portions of the side walls 6, 7 and 8, respectively. The side wall 5 has a bottom forming extension 18 defined therefrom by the score line 14 and this bottom forming extension has marginal flanges or laps 19 adapted to be folded up and adhered to the outer surfaces of the side walls when the container is set up or erected for use.

The flanges 15, 16 and 17 turn in and are adhered to the bottom forming extension 18 when the container is made up.

The top of the blank has a transverse score line 20 extending thereacross which, on the side walls 6 and 8 defines marginal flanges or laps 21 and 22, the latter being divided by a slit 23 into two sections. The inner section of the flange or lap 22 is adapted to be turned in as indicated by the lines 22' in Figure 3 to provide a reinforced rounded edge for the top of the side wall 8.

A similar reinforced rounded edge is formed on the adjacent part of the side wall 7 by a marginal flange or lap 24 on this side wall 7 and divided by the score line 20. The flange 24, like flange 22, is adapted to be folded in as indicated by the dotted lines 24'.

For its remaining width, the side wall 7 has an extension 25 defined therefrom by the score line 20. This extension 25 is long enough to extend from the side wall 7 to the side wall 5 when the container is made up, but, being narrower than the side wall 7, does not cover the entire top of the container.

The actual and final closure for the top of the container is effected by a top wall forming section 26 hinged to the side wall 5. This section 26 is large enough to cover the entire top of the container and when the container is set up for use covers and is adhered to the extension 25.

A slit 27 extending into the section 26 for a substantial distance provides for a movable flap portion 28 which closes the opening left by the insufficient width of the extension 25. It is to be noted, however, that the cover flap 28 is wider than this opening so that its inner edge portion overlies the extension 25 to be adhered thereto when the container is closed and sealed.

The movable cover flap is defined jointly by the slit 27 and a score line 29 on which the flap may hinge and swing to and from its closed position.

Along the three free marginal edges of the cover section 26 are flanges or laps 30, 31 and 32 adapted to fold over and be adhered to the outer surfaces of the side walls to secure the cover closed.

With the entire movable cover flap 28 swung open about the score line hinge 29, a comparatively large opening is provided to facilitate filling the container. For pouring out its contents the opening need not be so large, and preferably is smaller. Consequently, the movable cover flap 28 is divided by a score line 33 and a slit 34 extending across its flange 32, into an inner and outer section.

The outer section provides a hinged flap 35 which is opened to form a pouring opening at

the corner of the container defined by the junction of the walls 7 and 8. These walls as noted hereinbefore, have their upper edges rounded and reinforced by the inturned flanges 22 and 24.

Being relatively small, the hinged flap 35, reinforced by its side flanges 31 and 32, may be readily opened and closed after the seal is once broken.

The hinged flap 35 thus not only affords a convenient manner of opening the container to enable pouring the contents therefrom, but also serves as a closure or stopper to protect the contents after the container has been opened and partially emptied.

Attention is also directed to the fact that the top of the container, for much of its area, is of double thickness formed by the section 26 being superimposed on and adhered to the extension 25 and the flanges or laps on the side walls.

As is customary in paper containers of this type, liquid proofing is effected by coating all surfaces of the container with paraffin or other suitable waterproof substance prior to the filling of the container, and, as will be readily apparent to those skilled in the art, when so coated, the container will be exceptionally rigid and strong and by virtue of the location of its pouring opening will be easily emptied.

As will be apparent to those skilled in this art, the paraffining of the container interior is materially facilitated by the large filling opening. This large opening also enables the insertion of an expansible tool into the container to provide an internal support for the formation of the bottom closure; the formation of the top closure having been previously effected over a suitable internal support inserted through the open bottom of the body.

If desired the final sealing of the container (after filling) may be effected by merely adhering the hinged cover flap 28 including its outer smaller hinged portion 35 to the projecting portion of the extension 25 and by adhering its flanges 31 and 32 to the side walls of the body. While this forms an effective seal, it may be a bit difficult for the consumer to "pry" the hinged flap 35 open. The manner of sealing the filled container illustrated in Figure 5 is, therefore, more desirable.

However, before describing the sealing method shown in Figure 5, it is desired to direct attention to the specific construction of the container illustrated in Figures 4, 5 and 6. Generally, this container is like the one shown in Figure 1. The specific construction of the top and bottom closures, is, however, different. As a result of this difference, a triple thickness top and bottom is obtained.

To produce the triple thickness bottom the blank BB (Figure 4) is so formed that the side wall 7 has a full sized extension 36 which folds over half sized extensions 37 and 38 on the side walls 6 and 8, respectively, to provide two thicknesses inside the extreme bottom extension 39 on the side wall 5. This latter extension 39 has flanges 40 which fold over and are adhered to the sides of the body.

One of these flanges, the one adjacent to the half sized extension 37, is notched as at 41. While this reduces the width of the flange 40 at the back corner, it provides stock for increasing the length of the extension 37 and thereby provides a generally better construction.

In the formation of the top closure, the side walls 7 and 8 have flanges 42 and 43 folded over

and glued down as shown in Figure 4, to provide the reinforced rounded pouring edge. Preferably the flanges 42 and 43 are one continuous strip so as to continue uninterrupted around the corner formed at the score line 11.

The top edge of the side wall 8 outwardly of the flange 43 has a narrow extension 44 which is long enough to reach across the top to the side wall and thus cover the opening left between the edges of an extension 45 (on the side wall 8) and the adjacent side wall 5.

The top edge of the side wall 7 not taken up with the flange 42 has an L shaped extension 46 thereon. This extension is long enough to reach to the side wall 5 and is of the same width as the extension 45 which is somewhat greater than half the width of the container, the remaining distance defining the width of the opening. At its outer end the extension 46 is equal in width to the side wall 5 for a distance out from the side wall 5 far enough to cover the narrow extension 44.

Thus, when the extensions 45 and 46 are folded down and the extension 46 is folded thereover, a double thickness is obtained for the partially formed top, leaving a rectangular filling opening as long as the flange 43 and as wide as the flange 42.

The third thickness for the top closure is provided by an extension 47 on the side wall 5. This extension 47, like the bottom extension 39, is large enough to cover the entire area of the top and, like the extension 39, it has flanges 48 to fold over and be adhered to the side walls. A notched or stepped cut 49 in the extension 45 and the adjacent flange 48 is used to obtain maximum strength at the back corner the same as at the bottom.

The top extension 47, as in the previously described construction, is divided into the fixed portion 50 which is secured down in place when the container is set up for use, and a hinged cover 51 left free until after the container has been paraffined and filled. As before, the filling opening is large enough to allow an expansible internal supporting tool to be inserted for supporting the bottom during its formation.

After the container is filled, final sealing is effected in the manner shown in Figure 6. As here shown, a piece of suitable sealing material 59' is applied over the filling opening. If waxed glassine or other thin waxed paper is used no special adhesive is required as the wax coating fuses under heat and pressure. Obviously, other suitable sheet material like Pliofilm or Cellophane can be used for the seal.

If desired, an arrangement may be used whereby the sealing material is cut from a ribbon fed across the path of the containers as they leave the filling machine.

With a piece of the sealing material 59' covering the filling opening, the hinged cover 51 is brought down and secured in place. This cover, however, is divided transversely by a score line 52 into a rear section 53 and a front section 54. A slit through the flange 48 in line with the scoring 52 leaves the front section hingedly movable with respect to the rear section.

In applying the cover over the sealing sheet, the sheet is adhered all around the edges of the opening, as the hinge of the cover 51 is spaced rearwardly of the rear edge of the opening and the side of the cover overhangs the side of the opening. Any suitable means is employed to simultaneously adhere the sealing sheet all around

the edges of the opening and permanently adhere the rear section of the cover and its flange while the front section 54 is left free. This may be accomplished by coating the under surfaces of the rear section 53 and its flange with an adhesive while the front section is left uncoated, or by protecting the under surfaces of the front section or flap 54 and its flanges from adhesion to the sealing material.

10 The free hinged front section or flap is then temporarily secured in its closed position by an exterior seal 55 (Figure 7) which may be easily broken by the consumer to expose the thin sealing sheet. Puncturing the sealing sheet allows the contents to be poured from the container, and as will be clear, after puncturing the sealing sheet the opening thus formed may be covered by the hinged cover section or flap 54 which can be closed and opened at will.

20 Another manner of detachably securing the hinged front section or flap 54 down is illustrated in Figure 8. In this case one of the side flanges 48 has a tab 56 extended therefrom and adhered at its outer end to the side wall. A line of perforations 57 dividing the tab from the flange 48 is substantially in line with the lower edge of the portion of the flange 48 under it. The perforated tab portion is thus spaced a slight distance from the side wall to facilitate breakage along the perforations.

25 In the several embodiments of the invention hereinbefore described and as best shown in Figure 6 only the inner two edges of the pouring opening are bounded by flat top surfaces to which the sealing sheet may be adhered. Further improvement in the matter of final sealing is obtained through use of the construction shown in Figure 9. As here shown a flat topped marginal edge extends around the entire perimeter of the pouring opening. The flat topped marginal portions 60 at the outer pouring corner of the opening are formed by folding extensions of the flanges 22 and 24 in the manner specifically shown and described in the copending application of Lewis C. Brooks, Serial No. 463,099 filed October 23, 1942.

30 This provides a flat top surface all around the pouring opening to which the sealing sheet may be adhered. Obviously the specific formation of the shoulders 60, i. e., their cross sectional shape forms no part of this invention and may be of any design desired, but preferably the flanges 60 are held to a narrow width to minimize the interference with pouring.

35 What I claim as my invention is:

55 1. In a paper container of the character described: flat vertical side walls, the upper edges of all of which lie in substantially a common horizontal plane; a flat top wall closing the top of the container, said flat top wall having a corner portion thereof hinged on a score line so as to be movable to an open position providing a pouring opening at said corner of the container; and marginal flanges on the top edges of the side walls forming said corner folded and adhered to the inner surfaces of said side walls to provide reinforced flat top surfaces bounding the outer edges of the pouring opening.

60 2. An end closure for liquid-proof paper containers of the type made from a single blank and having a flat sided body comprising: flaps hinged to the edges of the body sides folded over and adhered to each other to form a multiple thickness wall closing all but one side and corner portion of the end of the container so as to leave an opening in said end closure communicating

with the entire interior of the container and of relatively large size for the admittance of a tool into the container and to enable coating of the entire interior surfaces of the container with a liquid-proofing medium; a flap hinged to the outermost of said superimposed flaps for closing said opening; and a sealing sheet of thin flexible material impervious to the contents for which the container is designed adhered to the edges of the opening under said hinged flap.

3. An end closure for a flat sided fiber container comprising: flaps folded in from certain of the side walls to partially close the container end and leave a relatively large sized filling and tool inserting opening through which access is had to the entire bottom of the container and through which the entire contents of the container may be quickly dispensed; an outer flap folded in from another side wall to overlie the other flaps, said outer flap being of a size to cover the entire end of the container and being cut and scored to divide the same into a fixed part and a hinged part, the fixed part being adhered to the flap surfaces under it and the hinged part being over said filling opening and being larger than the opening so that the flap portions to which the fixed part is adhered provide inset ledges under the hinged part; and a frangible seal adhered to said ledges and closing the pouring opening under the hinged part.

4. An end closure for a flat sided fiber container comprising: flaps folded in from certain of the side walls of the container to partially close the container end and leave a relatively large sized filling opening through which the entire contents of the container may be quickly dispensed, said filling opening enabling insertion of a bottom forming tool into the container, two sides of said pouring opening being defined by two side walls of the container; an outer flap folded in from another side wall of the container to overlie the other flaps, said outer flap being of a size to cover the entire end of the container and being cut and scored to divide the same into a fixed part and a hinged part, the fixed part being adhered to the flap surfaces under it and the hinged part being over the pouring opening and being of a size to cover the entire pouring opening and extend beyond the edges thereof defined by the first designated flaps so that the flap portions to which the fixed part is adhered at said edges of the opening provide inset ledges under the hinged part; and a frangible seal adhered to said ledges and to the adjacent side walls of the container to close the pouring opening under the hinged part.

5. In an end closure for flat sided fiber containers: an outermost flap folded in from one side wall of the container and covering the entire end of the container body, said outermost flap being scored and cut to divide the same into a fixed part and a hinged part; flanges on the fixed part permanently adhered to the adjacent side walls; flanges on the hinged part to overlie the adjacent side walls; a tab extended from one of the flanges on the hinged part having its outer end portion adhered to the adjacent side wall to hold the hinged part down, said tab having a row of perforations across it; and means for spacing the flange carrying the tab from the adjacent side wall adjacent to said row of perforations to facilitate breaking the perforated portion of the tab to sever the same from the flap and release the hinged part for opening.

6. A paper container comprising: a body hav-

ing flat side walls; flat top and bottom closures for the ends of the body, the top closure having a filling and pouring opening through which the entire contents may be quickly dispensed and through which an expansible supporting tool may be inserted into the container after the top closure has been formed to provide a support over which the bottom closure may be formed; said top closure comprising flaps hinged to side walls and folded in, one on the other, the under-flaps being of such dimensions as to close substantially only half the top of the container, the uppermost flap being of a size to cover the entire top and being adhered to the flap surfaces thereunder; said uppermost flap having a portion which overlies the part of the top not closed by the under-flaps defined from the remainder thereof by cut and scored lines so that said portion may be swung up on a hinge formed by one of the scored lines to provide a large filling opening through which the expansible supporting tool is insertable; and said hinged portion being divided by another score line into inner and outer sections hingedly movable with respect to each other, the latter section providing a dispensing lid; and overlapping parts on said hinged portion and the adjacent under-flaps adapted to be adhered after filling of the container.

7. A paper container of the character described comprising: vertical side walls all having their upper edges lying in substantially a common horizontal plane; a flap hinged to one of said side walls and extending across the top of the container, said flap being substantially half the width of the container so as to leave the remaining half of the top thereof open; and a cover forming section hinged to another side wall and overlying said flap and adhered thereto, said cover forming section covering the entire top of the container and having a corner portion thereof which overlies the part of the top not closed by said flap cut and hinged to be movable to and from a closed position, said hinged corner portion having a transverse score dividing it into inner and outer sections the latter of which covers the extreme corner so that upon being lifted a pouring opening results, said hinged corner portion being wider than the opening left by the first designated flap so that said first designated flap provides a ledge to which the hinged corner portion is adhered in sealing the container and which ledge cooperates with the upper edges of the side walls adjacent to said hinged corner portion to support the same.

55
